D10-116. OR D 12,047 EX

Design No. 12,047, dated November 30, 1880.

UNITED STATES PATENT OFFICE.

HENRY THAU, OF NEW YORK, N. Y.

DESIGN FOR A BOX-BELL.

SPECIFICATION forming part of Design No. 12,047, dated November 30, 1880.

Application filed September 23, 1880. Term of patent 7 years.

To all whom it may concern:

Be it known that I, HENRY THAU, of the city, county, and State of New York, have invented a new Design for Box-Bells, of which 5 the following is a specification.

The annexed photograph represents a front elevation of my newly-designed box-bell.

The leading features of the design consist in a shield-shaped base cast or struck up in 10 alto-rilievo with scroll-shaped projecting upper corners and a semicircular shell ornament between the scrolls; also, in the box or cover having molded corners and a central figure of a face in alto or bas relief.

15 A is the base of the box-bell, the general form of which is that of a shield having projecting scrolls B at the upper corners and a semicircular shell ornament, C, between the scrolls. The bands D, forming continuations 20 of the scrolls B, extend along the vertical edges of the base A and are curved outward, and at their lower ends are perforated by scrolls E which terminate beneath the bell. At the middle of the sides there are ornaments F, 25 composed of leaves and fruit. The cover G has molded corners H and a central ornament, I, consisting of a human face in alto-rilievo, partly surrounded with drapery.

Having thus described my invention, what I claim as new, and desire to secure by Letters 30 Patent, is—

1. The design for a box-bell herein shown and described, having the scrolls B and shell C on the base A.
2. The design for a box-bell herein shown 35 and described, having the scrolls B and E, the side ornaments, F, and the center ornament, C.
3. The design for a box-bell herein shown and described, having the molded corners H 40 and central figure, I, of a human face partly surrounded by drapery.

4. The design for a box-bell herein shown and described, having the scrolls B, shell C, ornaments F, and face I.

HENRY THAU.
